UNITED STATES PATENT OFFICE

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA

ELECTRIC TRAIN-WIRE COUPLING

Application filed October 16, 1925. Serial No. 62,827.

This invention relates to couplers and more particularly to an electric train line coupling.

In the operation of automatic train line couplers of the type shown in my prior pending application, Serial No. 568,245, filed June 14, 1922, where a movable contact carrier is projected by the operation of tappets upon the coming together of counterpart couplers, it has been found that in some cases, if cars come together at a high rate of speed, the contact carrier is liable to be shot forward so suddenly that the momentum may cause the carrier to overtravel, so that there is a possibility that the contact may become interlocked with the contacts of the counterpart coupler with consequent danger of jamming and breaking the contacts and the surrounding insulation.

The principal object of my invention is to provide means for preventing overtravel of the contact carrier and consequent injury to the contacts.

In the accompanying drawing, the single figure is a sectional view of an electric train line coupler head with my invention applied thereto.

As shown in the drawing, the coupler head may comprise a casing 1 containing a movable contact carrier 2, which includes a casing 3 and is provided with contacts 4 adapted when the carrier is projected to engage corresponding contacts of a counterpart coupler head, thereby completing the train line circuits. The contact carrier 2 also includes a frame 5, which is secured to the casing 3 by means of bolts 6, said contact carrier being adapted to be projected by force stored up through movement of a push rod 7 by impact with a meeting face of the counterpart coupler, as in my pending application hereinbefore referred to.

According to my invention a cushion gasket 8 of yielding material, such as rubber, is applied to frame 5 by means of a plurality of rivets 9, holes being provided in said gasket to receive said rivets, and since the gasket is made of yielding material, the holes may be stretched, so that the gasket can be applied over the heads of said rivets.

In operation, when the contact carrier 2 is

automatically projected to complete the train line circuits, the gasket 8 engages a face 10 of the casing 1 so as to prevent overtravel of the contact carrier and consequent possible damage of the contacts.

Having now described my invention, what I claim as new and desire to secure by Letters Patent, is:—

1. An electric train line coupler comprising a casing, a relatively movable contact carrier mounted in said casing and having contacts adapted to butt against corresponding contacts of a counterpart carrier, and a cushion member of yielding material carried by said carrier and adapted to engage the casing upon projection of the contact carrier and thereby yieldingly limit the outward travel of said carrier, said cushion member being sufficiently yielding to provide a cushion and sufficiently firm to act as a stop. 70

2. An electric train line coupler comprising a casing, a relatively movable contact carrier mounted in said casing and having contacts adapted to butt against corresponding contacts of a counterpart carrier, and a gasket of yielding material secured to said contact carrier and adapted to engage a meeting face on said casing upon projection of the contact carrier and thereby yieldingly limit the outward travel of said carrier, said gasket being formed of material sufficiently yielding to provide the desired cushioning effect and sufficiently firm to act as a stop. 75

3. An electric train line coupler comprising a casing, a relatively movable contact carrier mounted in said casing and having contacts adapted to butt against corresponding contacts of a counterpart carrier, and a resilient cushion member secured to said contact member and adapted to engage a face on said casing upon projection of the contact carrier and thereby yieldingly limit the outward travel of said carrier, said cushion member being so constructed that the member acts as a definite stop after a predetermined compression of the member. 95

In testimony whereof I have hereunto set my hand.

CLYDE C. FARMER.
